DESIGN FOR LEATHER OR SIMILAR ARTICLE

Justin Schiess, Englewood, N. J., assignor to R. Neumann & Company, Hoboken, N. J., a corporation of New Jersey

Application June 17, 1941, Serial No. 101,486

Term of patent 14 years

To all whom it may concern:

Be it known that I, Justin Schiess, a citizen of the United States, residing at Englewood, in the county of Bergen and State of New Jersey, have invented a new, original, and ornamental Design for Leather or Similar Article, of which the following is a specification, reference being had to the accompanying drawing, forming part thereof.

In the drawing

Fig. 1 is a plan view of a piece of leather illustrating my design, a complete unit of said design being embraced by the intersecting section lines, which unit is used as a repeat.

Fig. 2 is an enlarged sectional view taken on line 2—2 of Fig. 1.

I claim:

The ornamental design for leather or similar article, as shown and described.

JUSTIN SCHIESS.
